GAME APPARATUS

David C. Rockola, Chicago, Ill., assignor to Rock-Ola Manufacturing Corporation, Chicago, Ill., a corporation of Illinois

Application April 25, 1935, Serial No. 18,177

1 Claim. (Cl. 273—123)

This invention relates to a game apparatus. It is an object of this invention to provide an improved game apparatus which is relatively simple and inexpensive in construction and efficient in use.

5 Other objects will appear hereinafter.

The invention consists in the novel combination and arrangement of parts to be hereinafter described and claimed.

10 The invention will be best understood by reference to the accompanying drawing, showing the preferred form of construction and in which:

Fig. 1 is a fragmentary perspective view of a game apparatus embodying a preferred form of 15 the present invention;

Fig. 2 is a fragmentary top plan view of the preferred form of the invention;

Fig. 3 is a sectional view on line 3—3 in Fig. 2; and

20 Fig. 4 is a sectional view on line 4—4 in Fig. 2.

A game apparatus embodying a preferred form of the present invention is shown in the drawing, is therein generally indicated at 10, and comprises a cabinet 11 which includes an inclined playing board 12 having a pair of spaced ball exit openings 13 and 14 formed therein. Slidably mounted in the cabinet 11, below the inclined playing board 12, is a so-called "shuffle board" or ball retaining member 15 which is provided with an opening 16, and this opening 16 is adapted to be moved into registration with the ball exit openings 13 and 14, by movement of the ball-retaining member 15, so as to discharge balls from the latter to a point below the inclined playing board 12.

35 Mounted upon the inclined playing board 12 is a convoluted member 17 which has an end portion or convolution 18 which projects between the ball exit openings 13 and 14; this member 17 being mounted above the inclined playing board 12 by means of suitable supports 19. A rebound spring 20 is mounted upon the convoluted member 17 at one end thereof.

A played ball may enter into the convolutions of the member 17, from the inclined playing board 12, by way of the gate or entrance 21.

40 The foregoing arrangement is such that when a ball passes through the gate 21 into the convolutions of the member 17, it will, if it has suffi-

cient momentum, travel around the convoluted member 17 into the innermost convolution 18 thereof whence it will fall into the ball exit opening 14 in which it will be temporarily retained by the slidable ball retaining member 15 until the latter is shifted into ball releasing position, as is well understood in the art.

5 However, if the ball which passes through the gate 21 has relatively little momentum, and not sufficient momentum to carry it around the convoluted member 17 into the innermost convolution 18 thereof, it will gravitate back into the ball exit opening 13, by reason of the inclination of the board 12.

If a played ball strikes the rebound member 20 15 it will be reprojected by the latter up the inclined playing board 12.

20 When a played ball travels around the convolutions of the member 17 it moves in a whip-like action which is attractive to the player and adds to his interest in playing the game with which the accessory 17 is associated.

25 While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the 30 scope of the appended claim.

Having thus described my invention what I claim as new and desire to protect by Letters Patent is:

35 In a game apparatus of the type having a ball playing surface and means for projecting balls thereon, a ball trap comprising a wire-like spiral having an inner and an outer convolution and supported in a plane parallel to said surface at a distance therefrom, the said inner and outer convolutions thereof being adapted to overlie a pair of spaced ball-receiving apertures in the said surface and having a portion of said spiral lying between the said ball apertures, the outermost end of said spiral being provided with a substantially 40 co-extensive resilient buffer.

DAVID C. ROCKOLA.
